Primary Examiner — Cynthia Ramirez*Assistant Examiner* — Llorellys Martinez-Rivera*(74) Attorney, Agent, or Firm* — Muncey, Geissler, Olds & Lowe, P.C.(57) **CLAIM**

The ornamental design for a lens for lighting module, as shown.

DESCRIPTION

FIG. 1 is a front perspective view of a lens for lighting module showing our new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.
